UNITED STATES PATENT OFFICE

SIDNEY J. FINN, OF BEVERLY, MASSACHUSETTS, ASSIGNOR TO UNITED SHOE MACHINERY CORPORATION, OF PATERSON, NEW JERSEY, A CORPORATION OF NEW JERSEY

TRIMMING MACHINE

Application filed July 17, 1928. Serial No. 293,376.

This invention relates to trimming machines and is herein illustrated as embodied in a machine for trimming the linings of overshoes.

5 A type of arctic overshoe now in vogue for women is provided with a cuff at the top adapted to be turned up or down at the option of the wearer. The cuffs of such artics are commonly made of two layers of woven, 10 rubberized fabric, for example, plush, or corduroy, and they are attached to the tops of the uppers by lapped seams so that they must be bent or folded when turned down.

It is customary to provide the upper of an 15 overshoe of the type above described with a full lining of woven fabric and with a supplemental semi-lining of rubberized knitted fabric, comprising two upstanding tongues or strips, one arranged at the back of the shoe, 20 and the other arranged on the front or bellows portion. These tongues or strips are attached to the inner surface of the full lining by cement, and to insure a neat appearance at the top of the shoe they are trimmed flush 25 or parallel with the top of the upper after they have been attached. These trimming operations have heretofore been performed with scissors.

Accordingly, an object of the present invention is to provide a machine by which 30 these and similar trimming operations may be readily and conveniently performed. A problem peculiar to these trimming operations is that the bend or fold of the cuff is in 35 the way of trimming the back lining close to the root of the cuff, whereas no portion of the cuff lies adjacent to the front lining that projects above the top edge of the bellows portion of the upper. Again, as to the front 40 lining it is desirable to sever the surplus material flush with the upper edge of the bellows portion, but as to the back lining it is desirable to sever the surplus material along a line well below the top of the fold of the 45 cuff so that no edge of this lining portion will be visible even when the cuff is turned down.

To meet the dissimilar conditions above described, so that one machine may be used to perform both trimming operations referred to, a feature of the present invention

55 consists in a novel combination comprising the combination with trimming mechanism of work-supporting means provided with a plurality of work-supporting portions and mechanism for shifting the work-supporting means to place those portions alternatively in dissimilar positions to cooperate with the trimming mechanism. As illustrated, the work-supporting mechanism comprises a block adapted to enter the top of a shoe and 60 provided with two work-supporting surfaces either of which may be placed in a position to cooperate with a pair of rotary shears, one work-supporting surface being arranged to support the work at a considerable angle of 65 inclination relatively to the plane of the shearing cut to trim the lining portion that lies inside a cuff, while the other is arranged to support the work substantially at right angles to the plane of the shearing cut to trim 70 the lining portion that projects from the bellows portion of the upper.

75 The invention also provides manually operative mechanism by which the work-supporting means may be shifted at will to place either of the work-supporting surfaces of the block in operative position so that first one and then the other of these surfaces may be used to enable the operator to trim both the front lining and the back lining of a shoe 80 with one handling thereof.

85 Another feature of the invention consists in a novel type of trimming guard formed and arranged to prevent injury of the cuff portion by the trimming cutters and at the same time to permit severing the back lining, inside the cuff, on a line below the fold of the cuff. As shown, this guard comprises a thin circular disk arranged in front of one of the shearing cutters to fend the fold of the cuff or the previously trimmed edge of the bellows portion, as the case may be, from that 90 one of the cutters, the guard being rotatably mounted so that its edge will have rolling contact with the material being trimmed.

95 The features hereinabove mentioned and others are hereinafter described and claimed.

Referring to the drawings,

100 Fig. 1 is a side elevation, partly broken away, of a trimming machine embodying the

several features of this invention, the work-supporting means being shown in the position required for trimming the back lining of an overshoe;

5 Fig. 2 is a similar view of the upper portion of said machine with the work-supporting means in the position required for trimming the front lining of the shoe;

10 Fig. 3 is a front elevation of the machine structure shown in Fig. 2, the position of the work-supporting means corresponding to the position shown in Fig. 1; and

15 Fig. 4 is an elevation on a larger scale showing the shearing members and parts located adjacent to them, the assemblage corresponding to the showing in Fig. 1.

20 The illustrated machine is of the same general type as that more fully shown and described in Letters Patent No. 1,659,595, granted February 21, 1928, on an application filed in my name. For purposes of comparison, the frame 10, cutter shafts 12 and 14, rotary lapped shearing cutters 16 and 18, presser roll 20, feed roll 22 and an electric motor 24 for driving the cutter shafts are 25 substantially like the corresponding elements described in said patent. The cutter 16, being thin and sharp, does the cutting while the material to be severed is supported adjacent 30 to the plane of the cut by the less acute rim of the cutter 18 which is in front of the cutter 16. The cutter shafts 12 and 14 are connected by gearing (not shown) that causes them to rotate in opposite directions. The 35 feedroll 22 is fixed to the shaft 14, but the presser roll 20, while carried by the shaft 12, is not keyed to the shaft but may turn relatively thereto so as to turn consistently with the progress of the work rather than at a rotational speed equal to that of the shaft 12. 40 The presser roll 20 is in the form of a thin, annular flange while the feed roll 22 is provided with a groove that constitutes a counterpart of the flange so that the surplus material severed by the cutters 16 and 18 will be 45 gripped as shown in Fig. 4 and be fed away from the severing locality.

50 The arctic overshoe shown in the drawings is provided with an upper 26 made of textile fabric impregnated with a water-proofing compound. A cuff 28 comprising a plurality of layers of relatively thick textile material, such as plush is attached to the top margin of the upper 26 in lapped relation thereto, the seam being indicated at 30 in 55 Fig. 4. Overshoes of this type are commonly worn with the cuffs turned down as shown in the drawings but they may be worn with the cuffs turned up. It is common to line the 60 uppers at the front and back with strips or tongues 32 and 34 of knitted fabric. The strip or tongue 32 is from two to three inches wide at the top and is cemented to the bellows portion of the shoe upper, while the 65 strip or tongue 34 is usually about two inches

wide at the top and is cemented to the inner surface of the back of the shoe upper. These strips or tongues 32 and 34 initially project above the top of the shoe to provide for trimming them in conformity therewith. 70 Accordingly, each shoe has two projecting surplus portions α of lining material that must be severed after the shoe is otherwise nearly, if not quite, finished.

75 The machine already described in part is provided with a novel type of work-supporting means by which the aforesaid trimming operations may be accomplished rapidly and accurately with one handling of each shoe. A block 36 of a shape and size that enables it to be readily inserted into a shoe is movably attached to the frame 10 so that it may be placed in different positions to cooperate with the trimming mechanism. In the form shown, the supporting block 36 is provided 80 with a substantially horizontal work-supporting surface or bed 38 for use when trimming the front lining portion 32 and with an inclined work-supporting surface 40 for use when trimming the back lining portion 34. 85 As shown, this block is affixed to the front end of a horizontal rock-shaft 42 journaled in a bracket 44 affixed to the under side of the frame 10. The surfaces 38 and 40 are 90 diametrically opposite each other with regard to the axis of the rock-shaft, and the arrangement of the elements is such that these surfaces may be placed alternatively in front of the trimming mechanism and in 95 position to cooperate therewith by turning the rock shaft 180°. Preferably the surfaces 38 and 40 are convex, as shown in Fig. 3, to facilitate feeding the work, and the portion having the surface 40, which is used when trimming the back lining 34, is preferably 100 relatively narrow to avoid distorting the curvature of the cuff 28 around the back.

105 The machine is also provided with manually operative mechanism for turning the rock-shaft 42 back and forth to invert the block 36. A torsion spring 46 surrounds the rock-shaft 42 and serves to maintain the block normally in one of its operative positions. One end of this spring engages a 110 collar 48 affixed to the rock-shaft, while the other end engages a fixture, for example, a portion of the bracket 44. A pinion 50 affixed to the rear end of the rock-shaft is engaged by a gear segment 52 affixed to a 115 rock-shaft 54 journaled in bearings formed in a bracket 56. A collar 58 affixed to the rear end of the shaft 54 is provided with two shoulders one of which is arranged to engage a fixed pin 60 as shown in Fig. 1, while the other is arranged to engage the same pin as 120 shown in Fig. 2. The collar 58 and the pin 60 thus limit the turning movement of the rock-shaft 54 so that the turning movement of the block 36 will be limited to 180° and thereby 125 register the surfaces 38 and 40 of the block in 130

their respective operative positions. An arm 62 affixed to the rock-shaft 54 provides an operating connection with a flexible wire cable 64 that extends through a flexible metallic guide tube 66 to an operating treadle 68. The frame 10 is mounted on the top of a hollow, telescopic supporting column 70 the lower section of which is provided with a pedestal and with a fulcrum 72 for the treadle 68. The operating cable 64 and its guide tube 66 are arranged to extend through the column 70. The lower end of the operating cable 64 (see Fig. 1) extends through a hole in the treadle 68 and through a compression spring 74 and is anchored to a collar 76, the spring 74 providing a resilient connection to guard against pulling the cable 64 out of its connections so that the treadle may be depressed to the floor after the shaft 54 has been arrested by the pin 60 as shown in Fig. 2. A tension spring 78 normally supports the treadle in a raised position determined by an adjustable abutment 80 affixed to the column 70 in a position where it will be engaged by an upper surface of the treadle.

The work-supporting block 36 is normally maintained in the position shown in Figs. 1, 3 and 4 by the spring 46, and the treadle 68 is normally maintained in its raised position as shown in Fig. 1. Accordingly, the inclined supporting-surface 40 of the block 36 is maintained in front of the cutter 18 and adjacent to the trimming locality. Assuming that the cutters 16 and 18 are rotating and that the operator is about to trim off the surplus portion α of the back lining 34 of an overshoe, he places the shoe on the block 36 as shown in Fig. 1, so that the back of the shoe is inclined at a steep angle relatively to the vertical plane of the shearing cut. The cutters are thus enabled to sever the strip along a line below the bend or fold of the cuff as illustrated in Fig. 4 so that the trimmed edge of the lining will be concealed by the bend of the cuff. While the trimming is in progress the operator may assist or retard the feeding of the shoe by manipulation thereof. Having completed the trimming of the lining 34, the operator retracts the shoe from the cutters, depresses the treadle 68, turns the shoe toe uppermost as shown in Fig. 2, and presents the front lining portion 32 to the trimming mechanism. The horizontal work-supporting surface 38 of the block 36 is now in front of and in register with the trimming cutters and supports the lining portion 32 in a plane at right angles to the plane of the shearing cut. The top edge of the bellows portion of the upper may now be placed adjacent to the front face of the cutter 16 so that the front lining 32 will be severed flush with that edge, the surplus material α being engaged by the feed roll 22 and the presser roll 20 as formerly described.

To assist the operator in presenting and guiding the shoe so that the lining portions 32 and 34 will be trimmed as described, the illustrated machine is provided with a guard or trimming gage of novel construction and arrangement comprising a freely rotatable circular disk 84 the rim or edge of which rolls on the material to be trimmed while the front face thereof engages and guides the fold of the cuff 28 or the previously trimmed edge of the bellows portion, as the case may be. As shown, the disk 84 is provided with a stem 90 journaled in a bearing at the free end of an arm 86 mounted on a horizontal pivot pin 88. The pivot pin 88 extends through a stationary supporting bracket 92 secured to one side of the frame 10 by a clamping screw 94, the bracket having a horizontal slot 96 (see Fig. 1) to provide for registering the disk 84 with the rim of the lower cutter 18. A light compression spring 98 (Fig. 3) is arranged in a socket formed in the arm 86 and its upper end bears against an under surface of the bracket 92 to depress the disk 84 with a light pressure. The initial level of the disk may be regulated by an adjusting screw carried by the arm 86 and arranged to bear on an upper surface of the bracket 92. In practice the screw 100 should be adjusted to place the bottom of the disk 84 at or near the level of the intersection of the trimming cutters. The disk stands in front of the cutter 16 in lapped relation thereto and covers nearly the entire area of this cutter, but is preferably offset toward the feeding-in side of the cutters as clearly shown in Fig. 3 so that the vertical diameter of the disk will register with the point of intersection of the cutter where the actual trimming takes place. Again, the axis of the disk is slightly skewed (see Fig. 4) to provide for close trimming. The margin of the disk 84 is very thin to permit the bend of the cuff 28 or the top edge of the bellows portion of the upper 26, as the case may be, to approach nearly, if not quite, to the shearing plane, but at the same time the disk does not permit any element of the shoe except the surplus portions α of the lining portions to run between the cutters. The pivotal mounting of the arm 86 and the effect of the spring 98 cause the disk 84 to press the work against the rim of the cutter 18. Consequently, this cutter and the disk 84 constitute a work-feeding couple of which the cutter applies the feeding effort while the disk applies the gripping pressure. Thus, while this couple acts on the work in front of the cutter 16 the feeding couple 22, 20 acts on the severed portions α behind that cutter.

Having thus described my invention, what I claim as new and desire to secure by Letters Patent of the United States is:

1. A trimming machine comprising trimming mechanism, and work-supporting

means provided with a plurality of work supporting portions, said work-supporting means being movable to place said portions alternatively in dissimilar positions to cooperate with said trimming mechanism.

5. 2. A trimming machine comprising mechanism arranged to sever a marginal portion of sheet material projecting from the top of a shoe, work-supporting means formed and arranged to project into a shoe and provided with work-supporting surfaces angularly related to each other, and mechanism for shifting said means to place said surfaces alternatively in positions to cooperate with said severing mechanism.

10. 3. A trimming machine comprising cooperative shearing cutters and mechanism for operating them, work-supporting means formed and arranged to project into a shoe said means being provided with work-supporting surfaces angularly related to each other, and mechanism for shifting said means to place said surfaces alternatively in positions to cooperate with said shearing cutters.

15. 4. A trimming machine comprising trimming mechanism, a shaft, work-supporting means affixed to said shaft and provided with dissimilarly arranged work-supporting surfaces, and mechanism for shifting said shaft to place said surfaces alternatively in positions to cooperate with said trimming mechanism.

20. 5. A trimming machine comprising cooperative shearing cutters and mechanism for operating them, and work-supporting means provided with alternative work-supporting surfaces arranged to stand at different angles relatively to the shearing plane of said cutters, said means being movable to place one or another of said surfaces in position to cooperate with said cutters.

25. 6. A trimming machine comprising trimming mechanism, a rock-shaft, a block affixed to said rock-shaft and provided with a plurality of work-supporting surfaces dissimilarly related to the axis of the rock-shaft, and mechanism for turning said rock-shaft to place said surfaces alternatively in positions to cooperate with said trimming mechanism.

30. 7. A trimming machine comprising trimming mechanism, a rock-shaft, a block affixed to said rock-shaft, said block being formed and arranged to enter a shoe and having work-supporting surfaces diametrically opposite relatively to the axis of said rock-shaft, and mechanism for turning said rock-shaft to place said surfaces alternatively in positions to cooperate with said trimming mechanism.

35. 8. A trimming machine comprising trimming mechanism, a movable work-supporting member formed to enter a shoe to support the upper thereof, a treadle, and mechanism operated by said treadle to place said work-

supporting member in different positions to cooperate with said trimming mechanism in performing trimming operations on different parts of the shoe.

9. A trimming machine comprising trimming mechanism, an invertible work-supporting member pivotally supported adjacent to said trimming mechanism and having work-engaging portions diametrically opposite each other with regard to the pivotal axis of said member, and manually operated mechanism for inverting said member to place said portions alternatively in cooperative relation to said trimming mechanism.

10. A trimming machine comprising trimming mechanism, a work-supporting member arranged to turn about an axis and having differently shaped work-engaging portions, manually operated mechanism for turning said member about said axis, and means arranged to limit the turning movements of said member and thereby register said portions individually in cooperative relation to said trimming mechanism.

11. A trimming machine comprising trimming mechanism, a work-supporting member arranged to turn about an axis and formed to project into a shoe, said member having dissimilarly arranged work-engaging portions, manually operated mechanism for turning said member about said axis, and means arranged to register said portions individually in cooperative relation to said trimming mechanism.

12. A trimming machine comprising trimming mechanism, a work-supporting member arranged to turn about a horizontal axis and formed to project into a shoe to support the upper thereof, said member having a surface arranged to support one portion of the upper in an inclined plane and another surface arranged to support another portion of the upper in another plane, and manually operated mechanism for turning said member about said axis to place said surfaces alternatively in cooperative relation to said trimming mechanism.

13. A trimming machine comprising trimming mechanism, a work-supporting member arranged to turn about a horizontal axis and formed to project into a shoe to support the upper thereof, said member having a surface arranged to support one portion of the upper in a horizontal plane and another surface arranged to support another portion of the upper in another plane, and manually operated mechanism for turning said member about said axis to place said surfaces alternatively in cooperative relation to said trimming mechanism.

14. A trimming machine comprising trimming mechanism, constructed and arranged to execute a shearing cut, a work-supporting member arranged to turn about an axis and formed to project into a shoe to support the

upper thereof, said member having a surface arranged to support one portion of the upper in a certain angular relation to the plane of the shearing cut and another surface arranged to support another portion of the upper in another angular relation to said plane, and manually operated mechanism for turning said member about said axis to place said surfaces alternatively in cooperative relation to said trimming mechanism.

15. A cutting machine comprising a rotary power-driven work-supporting member formed and arranged to enter a shoe, a cutter arranged to cooperate therewith to sever a marginal portion of sheet material projecting beyond the top of the shoe, means for operating said cutter, and a rotary disk guard arranged in front of said cutter, the rim of said guard being arranged to roll on said 20 marginal portion and to press the latter against said work-supporting member.

16. A trimming machine comprising work-supporting means formed and arranged to enter a shoe provided with a downturned cuff at the top of the upper, a cutter arranged to sever lining material projecting from the upper inside the fold of the cuff, mechanism for operating said cutter, and a circular disk guard the rim of which is arranged to engage 30 the material being severed and a face of which is arranged to fend the fold of the cuff from said cutter so that said lining material may be severed on a line below the fold of the cuff.

17. A cutting machine comprising a rotary power-driven work-supporting member having a shearing edge, a rotary disk guard the rim of which is arranged to roll on sheet material lying on said member, means to cause 35 said guard to maintain pressure against said member, a cutter arranged behind said guard to cooperate with said shearing edge, and means for operating said cutter.

18. A cutting machine comprising two rotary coaxial work-feeding members, two presser rolls arranged to cooperate with said members respectively to grip an element of sheet material, one of said feeding members having a shearing edge between said presser rolls, a cutter arranged to cooperate with said 50 edge to sever the sheet material with a shearing cut, and means for operating said cutter.

19. A lining-trimming machine comprising a pair of rotary shearing cutters one of which is formed and arranged to enter the top 55 of a shoe, means for driving said cutters, a work-support arranged in front of one of said cutters and formed to enter the top of the shoe, and a rotary disk guard arranged in front of and in lapped relation to the other 60 one of said cutters to prevent the top of the shoe from running between the cutters while a projecting portion of lining material is being severed by the cutters.

20. A cutting machine comprising a rotary power-driven member having a shearing

edge, a cutter arranged to cooperate with said edge to sever sheet material with a shearing cut, means for operating said cutter, and a circular rotary guard arranged in front of said cutter, said guard being spring-pressed 70 toward said power-driven member to develop a work-feeding action by the latter.

In testimony whereof I have signed my name to this specification.
